United States Patent Office

Des. 218,275

Patented Aug. 11, 1970

218,275

DESOLDERING TOOL

Alvis R. Knowles, Torrance, Calif., assignor to Eldon Industries, Inc., Hawthorne, Calif., a corporation of California

Filed Oct. 9, 1968, Ser. No. 13,895

Term of patent 14 years

Int. Cl. D8—02

U.S. Cl. D8—30

FIG. 1.

FIG. 2.

FIG. 3.

FIG. 4.

FIG. 5.

FIG. 1 is an isometric view of the desoldering tool embodying the design of my invention;

FIG. 2 is a side elevational view thereof;

FIG. 3 is a front elevational view thereof;

FIG. 4 is a top elevational view thereof;

FIG. 5 is a bottom elevational view thereof.

I claim:

The ornamental design for a desoldering tool, substantially as shown and described.
